ROTARY DRYING APPARATUS

Application filed March 12, 1930. Serial No. 435,169.

This invention relates to drying apparatus and particularly to drying apparatus of the rotary drum type in which material comprising solid material to be dried is delivered in 5 suitably crushed, ground, or divided condition into one end of a drum continuously rotated on an axis which is generally, though not necessarily slightly inclined to the horizontal, said material being heated during its 10 passage through the drum, as for example by passing a gaseous drying medium such as a body of hot combustion gases through said drum, so as to drive off moisture therefrom, and the dried material being removed from 15 the other end of the drum.

An important object of this invention is to provide a drying apparatus of this type so designed as to minimize or substantially prevent the leakage of air into the drum or of 20 gas out of the drum at the point where the material is fed into and removed from said drum, as well as the escape of dust or finely divided material from the material being dried. In drying apparatus of the type in 25 which a hot gaseous drying medium is passed through the drum it is necessary to make connections at each end between the rotating drum and suitable fixed structures so as to provide for inflow and outflow of such drying 30 medium and it is also necessary to provide for continuous or intermittent introduction of material to be dried to one end and for continuous or intermittent removal of the dried material from the other end. In the driers 35 now in use, these connections and material inlet and outlet means are such as to permit either outward leakage of the hot drying medium or inward leakage of the outside air, either of which decreases the drying efficiency 40 of the apparatus. Any mechanical means of sealing the leakage at this point, tight enough to be effective causes a great deal of friction between the stationary and rotating parts, as well as requiring constant adjustment to 45 compensate for wear. The forms of apparatus now in use also permit "dusting", that is, the escape of more or less of the more finely divided portions of the solid material being fed to or delivered from the drying apparatus. This "dusting" not only represents

a loss of material, but is also frequently objectionable as constituting a nuisance due to the introduction of this material into the surrounding atmosphere.

According to my invention the above disadvantages are overcome by providing the 55 rotating drum with an end wall closing off the major portion of the cross sectional area of the drum at each end thereof; said drum being preferably further provided with a 60 central passage means of relatively small cross-section as compared to the drum, extending through the end wall at the lower or material outlet end of the drum and secured to rotate with said drum, suitable means for 65 maintaining a positive inflow of hot gaseous drying medium through said passage means, another central passage means, also of relatively small cross section, opening through 70 the end wall at the upper or material inlet end of the drum and secured to rotate with said drum, and suitable means for maintaining a positive outflow of spent drying medium through said last named passage means; and by also providing means for 75 feeding the material to be dried into said drum, and for delivering the dried material from the other end of the drum, independently and separately from said inlet and outlet passage means for the drying medium, 80 and in such manner that the solid material itself is caused to form a seal to substantially prevent inflow or outflow of air or gas through said material feeding or delivering means. The means which I use for feeding 85 and delivering the solid material comprises essentially continuous passage means extending around the axis of the drum throughout at least substantially one complete revolution, said passage means opening exteriorly 90 of the drum at one end and opening into the interior of the drum at the other end, so that material may be caused to pass through said passage means upon rotation of the drum while maintaining at all times a body of material in said passage means at the lower part 95 of the drum of sufficient size to serve as a seal against passage of gas or air. At the material inlet end of the drier the passage means are so arranged that rotation of the drum in 100

the direction of normal operation will cause the solid material to pass in a direction from the exterior opening to the opening into the interior of the drum, and suitable means are provided for supplying material to position to enter said exterior opening. At the material discharge end of the drier the passages are arranged in reverse manner, that is, so as to provide for passage of the material, 10 upon normal rotation of the drum, in a direction from the interior opening to the exterior opening, and suitable means are provided for discharge of material from said exterior opening.

15 In order to provide for more nearly continuous delivery of the solid material into and out of the interior of the drum I prefer to provide a plurality of such passage means at each end of the drum, each of said passage 20 means being provided with openings at each end and the openings of the respective passage means being spaced angularly of the drum. Said passage means at each end are arranged for passage of the material there- 25 through in parallel. As the exterior opening of each material inlet passage moves through the lower portion of its path of revolution a certain charge of solid material enters through said opening and such material 30 passes continuously through said passage means upon continued rotation of the drum and is delivered to the interior of the drum through the interior opening of said passage when said opening is in position to permit de- 35 livery of such material therethrough by gravity. Similarly, as the interior opening of each passage at the material outlet end of the drum passes through the lower portion of its path of revolution, a portion of the material 40 from the interior of the drum enters said passage and passes around therein and is dis- charged from the exterior opening when said opening is in position to permit such dis- charge by gravity. The portions of material 45 thus contained in the respective passage means are sufficient to substantially obstruct the passage at all times against passage of gas or air therethrough.

50 A further object of the invention is to provide improved means for feeding the material to be dried into the drying drum and particularly to provide feeding means adapted to elevate such material from a position beneath the drum and deliver the same into the interior of the drum, thus permitting the material to be delivered to the drum from storage means at a lower level than would otherwise be possible without requiring the use of auxiliary elevating means.

55 A further object of the invention is to provide means for diverting the material fed into the drum away from the region adjacent the outlet passage for the drying me- dium, so as to largely prevent the drying medium from picking up the finely divided

portions of such material and carrying the same away in suspension.

A further object of the invention is to pro- 70 vide, in connection with a stack communicat- ing with the central outlet passage for the drying medium, an advantageous arrangement for return to the material feeding means of solid material carried away by the drying medium and deposited in said stack.

A further object of the invention is to pro- 75 vide means within the drum for controlling the rate of feed of solid material there- through so as to provide for the proper contact of such solid material with the drying 80 medium. A particular object in this con- nection is to provide means whereby the rate of movement of the solid material longitudinally of the drum is controlled in accordance with the size of the individual particles or 85 fragments thereof, so that particles of rela- tively larger size are caused to move more slowly through the length of the drum and are thus subjected to the drying action for a longer period of time than the particles of 90 relatively smaller size, thus tending to pro- 95 mote uniform drying of the material regard- less of the size thereof.

A further object of the invention is to pro- 95 vide improved means for effecting dis- charge of the dried solid material from the 100 interior of the drum, and a particular object in this connection is to provide for dis- charge of all of the material through a central discharge opening of smaller diameter than the shell of the drum. Due to the small- 105 er diameter of this discharge opening, the lower portion of said opening is at a higher level than the lower portion of the periphery of the drum, and the material is, therefore, discharged at a higher level than would be 110 the case if it were merely permitted to dis- charge from the drum at the lower portion of the periphery thereof. This raising of the level of discharge of the dried material may be of advantage in certain cases. As for in- 115 stance making it unnecessary to either ele- vate the dryer or dig a pit for an elevator boot when the dryer discharges into an ele- vator.

The accompanying drawings illustrate em- 115 bodiments of my invention and referring thereto:

Fig. 16 is a transverse section on line 16—16 in Fig. 13.

30 The form of apparatus shown in Figs. 1 to 5 inclusive comprises a rotatably mounted drum including a cylindrical shell 1 of any suitable length and diameter, and end plates or walls 2 and 3 secured respectively to the upper and lower ends of said shell in any 35 suitable manner and serving to close the respective ends thereof throughout the major portion of the cross sectional area of the drum. Said drum may be rotatably supported and driven in any suitable manner and is shown 40 as provided with two track rings 4 supported on rollers 5 mounted on supports 6. Rotation of the drum may be effected by driving some or all of the rollers 5, or otherwise, in the usual manner of such rotary drying apparatus, for example a motor 7 may be provided, driving bevel gear 7a meshing with bevel gear 7b attached to one of the rollers 5 as shown in Fig. 4. The drum is shown as mounted for rotation about an axis which is 45 inclined slightly downward from the material inlet end to the material outlet end thereof, although such inclined mounting is not essential to my invention.

50 At the upper or material inlet end of the drum the end plate 2, or, if desired, a separate plate or wall, extends out beyond the circumference of the shell 1 as indicated at 2' and an annular flange 8 projects from the outer edge of the portion 2', said flange being 55 preferably provided with an inwardly inclined rim or lip 9 so that the space within said flange and lip serves as a hopper adapted to receive and maintain a body of solid materials to be fed into the drum. A tubular 60 drum throughout at least substantially one

plate 2 and projects outwardly therefrom. Said tubular member opens into the interior of the drum through the central portion of end plate 2 and constitutes a central outlet passage for the spent gases or other drying medium. Said tubular member may be frusto-conical in shape as shown, and the outer end portion 10' thereof, whose diameter is relatively small as compared to the diameter of the cylindrical shell 1, for example from about $\frac{1}{4}$ to $\frac{1}{3}$ as great, extends through an opening 11 in the side wall of a stack 12. Said tube fits rotatably within said opening and should fit fairly tightly therein.

65 The solid material to be dried may be fed into the receiving hopper of the drum in any suitable manner, for example by means of an inclined chute 13 leading from a storage bin or hopper 14, said chute extending, for example, at one side of the stack 12, as shown in Fig. 5 and having its discharge opening 15 projecting over the lip 9 in position to deliver material into the space within said lip. In order to provide for return to the drying drum of any finely divided solid material carried over into the stack and subsequently settling therein, the lower portion of said stack below the opening 11 may be provided with a collecting pocket having an inclined bottom 16 and a chute 17 may be provided leading from the bottom of said pocket to a position over the lip 9. Said chute may be normally closed by a gate 18 having handle means 19 whereby said gate may be opened.

70 The material inlet passage means are shown as provided by means of a plate 20 extending outwardly from the shell, parallel to and spaced from the plate portion 2', and a plurality of concentric partition plates 21, 22, 23 and 24 extending between plate 2' and plate 20. In the example shown, there are three inlet openings 25a, 25b and 25c, equally spaced around the drum and establishing communication between the hopper space inside the flange 9 and the space between the two outer partition plates 23 and 24, but it will be understood that any suitable number of such openings may be provided. Each of the intermediate partition plates 21, 22 and 23 is provided with three openings 26, and inclined deflectors or partition plates 27 connect the adjacent concentric partitions at opposite sides of said openings. The shell 1 is also provided with three openings 28a, 28b and 28c establishing communication between the space between said shell and the inner partition plate 21, and the interior of said shell. The above construction, therefore, serves to define three separate passage means indicated at 29a, 29b and 29c for conducting material

75 to be dried from the respective openings 25a, 25b and 25c to the corresponding openings 28a, 28b and 28c, during rotation of the drum. Each of said passages extends around the member 10 is secured centrally of the end 80

complete revolution, and preferably throughout somewhat more than 360° , and extends progressively inwardly of the drum from the position of the exterior openings 25a, etc., to the position of the interior openings 28a, etc. I prefer to provide deflector plates 30 secured to the end plate and projecting into the interior of the drum between the respective interior openings 28a, etc. and the center of the drum, as shown in Figs. 1 and 2.

At the lower or material outlet end of the revolving drum, a cylindrical fire box 31 extends through the end plate 3 and is secured to rotate with the drum, for example by being secured to said end plate in any suitable manner. Said fire box opens at its inner end as at 32 into the interior of the drum and serves as a passage means for admission of drying medium to the interior of said drum. Said passage means, as shown, is preferably of materially smaller cross section than the cylindrical shell 1; for example, the diameter thereof may be from about $\frac{1}{5}$ to $\frac{1}{4}$ the diameter of said shell. Said fire box may be lined with suitable refractory material 33, and a burner 34 for liquid, gaseous or solid fuel projects through the open outer end 35 of said fire box, whose interior also serves as a combustion chamber for the fuel admitted to said burner. It will be understood that other means for maintaining an inflow of hot gaseous drying medium through the central passage 31 may be used instead of that shown in the drawings, or that any other suitable means may be employed for heating the material passing through said drum.

The material outlet passage means are shown as provided by means of a plate 37 outside the end plate 3 and spaced from and parallel to said end plate, an annular plate 38 and a plurality of concentric partition plates 39, 40, 41 and 42 within said annular plate, and suitably spaced from one another, all of said partition plates extending across between the end plate 3 and plate 37. I have also shown three material outlet openings 44a, 44b and 44c, equally spaced around the drum and establishing communication between the interior of the drum adjacent the periphery thereof and the space between the plates 3 and 37 and between the plates 38 and 39, it being understood, however, that any suitable number of such openings may be provided. Each of the intermediate partition plates 39, 40 and 41 is provided with three openings 45, and inclined deflectors or partition plates 46 connect together the adjacent concentric partitions at the opposite sides of said openings. The inner partition plate 42 is also provided with three discharge openings 47a, 47b and 47c, equally spaced around said partition and establishing communication between the space between said partition plate and the adjacent partition plate 41 and the annular discharge space 48 between

said inner partition plate and the fire box 31, said discharge space opening exteriorly of the drum. The above construction, therefore, serves to define three separate passage means indicated at 49a, 49b and 49c for conducting solid material from the respective openings 44a, 44b and 44c to the corresponding openings 47a, 47b and 47c during rotation of the drum. Each of said passages extends around the drum throughout at least substantially one complete revolution, and preferably throughout somewhat more than 360° , and extends progressively from the position of the interior openings 44a, etc. to the position of the exterior openings 47a, etc.

Discharge of the material from the space 48 may be facilitated by means of the outwardly inclined or flared annular apron 51 projecting from the edge of the inner partition plate 42, and a suitable discharge hopper or bin 52 may be provided for receiving the material discharged over said apron and delivering the same to any suitable conveying or storage means or the like. Additional support for the fire box 31 may be provided by the radial arms 53 secured to said fire box and to the outer edge portion of apron 51. In order to insure the maintenance of a bed of solid material of sufficient depth adjacent the openings, 44a, etc., the shell 1 is preferably provided with an outwardly inclined or flared portion 54 immediately above the end plate 3, the plates 3 and 37 being of somewhat greater diameter than the main portion of the shell 1, and the openings 44a, etc., being located adjacent the periphery of this flared portion, so that when said openings are at the lower part of their path of revolution they will be at the bottom of the pocket-like space 55 thus provided, for maintaining a bed of solid material of increased thickness in position adjacent said openings.

It is entirely within the scope of the present invention to employ a shell whose interior is substantially smooth and unobstructed throughout its length, but I prefer to provide means within said shell for controlling the rate of longitudinal movement of the solid material therethrough. Such means may comprise, for example, a plurality of annular baffle members 57 extending around the drum at any suitable positions longitudinally thereof and inclined inwardly toward the material inlet end of the drum. The action of said baffles in retarding or controlling the longitudinal movement of the material through the drum will be described more fully herein-after.

Additional means for this purpose are also shown as comprising annular screen members 58 extending around the interior of the drum and at any suitable positions longitudinally thereof and also preferably inclined inwardly toward the material inlet end of the drum. Said screens may be supported in any

suitable manner as, for example, by means of supporting frames indicated at 59. Said screens are of such mesh that the finer portions of the material to be dried will pass therethrough with relative ease, while the 5 larger particles or fragments of such material will pass therethrough with difficulty or will be prevented from passing through the regular meshes thereof. In case the solid material being dried is of such nature that the 10 larger fragments thereof will not be broken up by the agitation, attrition or abrasion to which they are subjected during passage through the drum, to sufficiently small size to 15 pass through the meshes of said screen members, said screen members may be provided with a suitable number of relatively large openings 61 to permit passage therethrough of such larger fragments upon encountering such relatively large openings, but it will be 20 understood that for use on materials of such friable nature as to be broken up by the agitation to which they are subjected in passing through the drum, and particularly when the 25 moisture is removed therefrom by the drying medium, such larger openings 61 may be omitted, as explained hereinafter. It will be noted that the baffle members 57 and the 30 screen members 58 preferably do not extend entirely across the interior of the drum, so as to leave a relatively free space through the center of the drum for the passage of the hot 35 drying medium therethrough.

The drum may also advantageously, though 40 not necessarily, be provided with lifting vanes 63 extending longitudinally of the drum and spaced at any suitable angular positions 45 therein, said lifting vanes being preferably inclined inwardly and in the direction of rotation of the drum, so as to cause the solid material to be lifted to greater height at the rising side of the drum than would otherwise be the case, and thus increase the agitation of the material and the contact thereof with the 50 hot drying medium.

The operation of the above described apparatus is as follows: The material to be dried comprising, in general, solid material in a suitable state of division, together with 55 more or less water or other liquid material, is delivered through feed chute 13 into the hopper space provided within the flange 8 and lip 9 at the lower portion of the drum. Such material may, in some cases, contain 60 free water or other liquid, so as to constitute a wet fluent mass, or the water or other liquid may be completely absorbed or otherwise held by the solid material, so as to form a mass of more or less wet fragments or particles. Simultaneously with the delivery of 65 such material, fuel is delivered through burner means 34 and burned within the combustion space inside the fire box 31, in the presence of air drawn in through the opening 35. The hot combustion gases thus pro-

duced pass through the open inner end 32 of the fire box through the length of the rotating drum and thence through the passage means 10 and upwardly through stack 12. The draft thus produced serves to maintain a positive inflow of hot gaseous drying medium through the passage means within the fire box at the material outlet end of the drum and a positive outflow of spent drying medium through the passage means 10 at the 70 material inlet end of the drum. The intensity of such draft and consequently the rate of flow of drying medium through the drum may be controlled by regulating the supply of fuel in any suitable manner and also by 75 suitable draft regulating means such as damper 65 in stack 12.

The material fed on to the lower portion of flange 8 and lip 9, passes through the several material inlet openings 25a, 25b and 25c 80 as such openings successively reach the lower portion of the drum, and it may be seen by reference to Fig. 2 that the continuous rotation of the drum will cause such material to pass inwardly through the corresponding 85 passage means 29a, 29b and 29c until it reaches the openings 28a, 28b and 28c, through which such material is delivered into the interior of the drum during the upward 90 movement of such openings, for example from the position of the opening 28a to the position of the opening 28c in Fig. 2. It will also be seen that the material in the respective 95 passage means is always in position at the lower portions of the several passages in 100 sufficient amount to substantially completely obstruct the passages as indicated at F in Fig. 2 and thus prevent inflow of air or outflow of gaseous drying medium through such 105 passages. In this form of the invention the several passages 29a, etc., extend progressively inwardly radially of the drum and hence serve to elevate the material from the level at which it is delivered upon the flange 110 8 and lip 9 to the level of the lower portion of the interior of the drum. When the level of the supply bin or hopper 14 is fixed, this arrangement of the passages is of advantage, as it permits the material to be delivered by 115 gravity into the material receiving space above said flange and lip and to be thus elevated sufficiently to reach the interior of the drum, thereby eliminating the necessity of providing other elevating means for this 120 purpose.

It will be evident that the delivery of material through each of the openings communicating with the interior of the drum will, in general, be substantially completed by the time such opening reaches the position of the opening 28c in Fig. 2, but the deflector plates 30 may nevertheless be of advantage in preventing any of such material from being delivered into too close proximity to the outlet 125 passage 10 and thus being picked up and 130

carried away by the outgoing gaseous medium. It will be seen that one of such deflector plates is in such position as to lie substantially directly beneath each of said openings in its passage from the position of the opening 28c to its uppermost position, and that the inclination of such plate is such as to divert the falling material, indicated at G, away from the opening into the passage 10 and thus prevent entrainment of such material as above described.

Due to the inclination of the axis of the drum (or due to the continual inflow of material at one end in case the axis is not inclined), and the continued rotation thereof, the material is caused to pass gradually lengthwise of the drum from the material inlet end to the material outlet end. Furthermore, such material is continually lifted at the rising side of the drum and caused to roll or fall downwardly through and in contact with the gaseous drying medium. This lifting of the material is enhanced by the lifting vanes 63, which thus cause the material to be brought into contact with the gaseous drying medium throughout a larger portion of the cross section of the drum than would otherwise be the case. The material is thus heated by the drying medium, so as to cause evaporation of water or other liquid therefrom, and the evaporated liquid is carried away with the spent drying medium.

In the longitudinal movement of the material through the drum, the upwardly and inwardly inclined annular vanes or baffle members 57 serve to retard the progress of such material to a certain extent and to tend to throw the material back toward the upper end of the drum and maintain at the lower part of the drum through the length thereof, a bed of material of a depth at least equal to the distance to which said baffles project inwardly. Furthermore, the frusto-conical screen members 58 serve to selectively retard the larger particles or fragments of solid material. Particles or fragments of solid material of less size than the meshes of said screens will pass readily therethrough while larger particles or fragments will be held back by the meshes of said screens and thus subjected to a longer period of contact with the drying medium. This is a desirable feature, since it is evident that a longer period of contact with such drying medium is required in order to effect heating and evaporation of liquid throughout such larger particles or fragments than is required in the case of smaller size material. In case the screens are provided as shown with relatively larger openings 61 at suitable intervals, such larger particles or fragments may eventually be permitted to pass through such relatively large openings, but it will be evident that, due to the relatively small number of such openings, the larger size material will

be retarded appreciably before encountering one of such larger openings and passing therethrough. As mentioned above, in case the material is of such easily friable nature as to be all reduced to sufficiently small size to pass through the regular meshes of the screen members, due to the agitation of such material within the drum, and particularly after removal of water or liquid therefrom, the relatively large openings 61 may be omitted, in which case all of the larger particles or fragments will be held back by the screen members until they are so reduced to proper size to pass therethrough.

With an apparatus of a given size, the rate of feed of material to be dried is so regulated with respect to the rate of supply of gaseous drying medium that such material will be sufficiently dried by the time it reaches the lower or material outlet end of the drum. Upon reaching this end of the drum, the material collects in the lower portion of the pocket 55 and passes thence through the several material outlet openings 44a, 44b and 44c. By reference to Fig. 3 it will be seen that the rotation of the drum causes such material to pass through the corresponding passages 49a, 49b and 49c to the discharge openings 47a, 47b and 47c. The movement of such material through such passages, and the manner in which such material serves to obstruct such passages and prevent inflow of air or outflow of gaseous drying medium therethrough is substantially the same as described above in connection with the material inlet end of the apparatus. Particular attention, however, may be called to the fact that the discharge space 48 into which the material is delivered by the openings 47a, etc., and the discharge apron 51, are of materially less diameter than the shell 1, and that the arrangement of the passages 45a, etc., so as to extend progressively inward radially of the drum serves to elevate the material from its position adjacent the periphery of the interior of the drum to the position of such relatively restricted discharge space and apron. This is also of advantage, since the discharge of the material through an annular discharge space of relatively small diameter causes less agitation of the material and also confines the discharge thereof to a smaller stream than would be the case if the material were discharged through a space and over an apron of a larger diameter equal to that of the drum itself, and thus minimizes the "dusting" of such material, that is to say, the levitation of the finer portions thereof into the air and consequent loss of such material. The dried material is delivered over the apron 51 into hopper or bin 52, whence it may be delivered into any suitable conveying or storage means.

In some cases it may be desirable to locate the means for supplying the material to be dried directly in line with the central vertical

plane of the drum, and such an arrangement is shown in Figs. 6 and 7. The material supply bin or hopper 14' is in this case provided with an inclined delivery chute 13' extending directly beneath the tubular gas outlet 10 and opening into the material receiving space within the flange 8 and lip 9 centrally of the lower portion thereof. The stack 12' may in this case be located somewhat to one side of the drum and may be connected to the tubular gas outlet 10 by means of an inclined flue 66 whose lower end is provided with an elbow 67 for connection to said tubular outlet. Said lower end of flue 66 may be mounted on suitable supporting means such as 68. The return of dust carried over into the inclined flue 66 may be provided for in this case by means of a dust return pipe or conduit 69 leading from the lower end of said flue adjacent elbow 67 to the feed chute 13' and having a gate 70 adapted to be normally closed to prevent inward leakage of air through said pipe but to be opened when desired, to permit the dust collected above said gate to return to the feed chute 13'. The operation of this form of the invention is substantially the same as above described and is believed to require no further description.

Various modifications may also be made in the arrangement of the passages for effecting movement of the material to be dried into the interior of the drum and movement of the dried material out of the drum while preventing leakage of gas or air out of or into the drum. For example, as shown in Figs. 8 to 12 inclusive, said passages may have their convolutions or turns successively displaced linearly of the drum instead of radially thereof. In this case the material inlet passage means are shown as provided by means of a cylindrical wall 72 surrounding and spaced from a portion of the shell 1 adjacent the material inlet end thereof, and a series of annular partition plates 73 extending transversely of the space between plate 72 and shell 1 and serving to divide such space into a suitable number of annular passages. The first partition plate 73' is shown as provided with three inlet openings 25a', 25b' and 25c', and each of the intermediate partition plates is provided with three openings 26'. Inclined deflectors or partition plates 37' connect the adjacent partitions 73 at opposite sides of said openings. The shell 1 is also provided with three openings, two of which are shown at 28a' and 28b', establishing communication between the interior of the drum and the space between the last two partitions 73. The direction of inclination of the deflectors 27 is such as to effect progressive displacement of the material through the corresponding opening 26' in a direction from the openings 25a', etc. toward the openings 28a', etc. As in the form of the invention first described, the above construction serves to define three

separate passage means indicated at 29a', 29b', and 29c' respectively, for conducting the material to be dried from the respective openings 25a', etc. to the corresponding openings 28a', etc. during rotation of the drum. Each of said passages, as before, extends around the drum throughout approximately 360° or more, but extends in this case progressively linearly of the drum from the position of the exterior openings 25a', etc. to the position of the interior openings 28a', etc.

The end plate 2 of the drum is shown as provided as before with a centrally located tubular gas outlet passage 10 which may be connected to a stack in any suitable manner, for example as shown in Fig. 1 or in Figs. 6 and 7. The flange 8' in this case extends from the outer edge of the first partition plate 73' and is shown as comprising a continuation of the cylindrical wall 72. Said flange is provided as before with an inwardly extending lip 9' serving to define a material receiving space within said flange and lip for receiving material from suitable feeding means, for example such as above described and holding the same in position to enter the exterior opening 25a', etc.

The other end of the drum is provided in this case also with a cylindrical fire box 31 having burner means 34 extending into the outer end thereof, said fire box extending centrally through the lower end plate 3' and being directly secured thereto in any suitable manner.

The material outlet passage means are shown as provided by means of a cylindrical wall 75 surrounding and spaced from a portion of the shell 1 adjacent the material outlet end thereof, and a plurality of annular partition plates 76 extending transversely of the space between said wall and shell. The first of the partition plates 76 is shown as comprising an outward continuation of the end plate 3'. The shell 1 is shown as provided with three material outlet openings, two of which are indicated at 44a' and 44b' equally spaced around the drum and establishing communication between the interior of the drum and the passage between the first two partitions 76. The last partition plate 76' is provided with three discharge openings 47a', 47b' and 47c' also equally spaced around the drum and establishing communication between the space between the partition plate 76' and the next partition 76 and the exterior of the drum. Each of the intermediate partition plates 76 is provided with three openings 77, and inclined deflectors or partition plates 78 connect together the adjacent partition plates 76 at opposite sides of said openings, said deflectors being inclined in such direction as to progressively displace the material through the openings 77 in a direction from the openings 44a', etc. toward the openings 47a', etc. There are thus pro-

vided three separate passage means indicated at 49a', 49b' and 49c' for conducting the dried material from the respective openings 44a', etc. to the corresponding openings 47a', etc. during normal rotation of the drum, and each of said passages extends around the drum throughout approximately 360° or more and extends progressively linearly of the drum from the position of the first mentioned openings to the position of the last mentioned openings. The end of the cylindrical wall 75 may be provided with an outwardly inclined or flared annular apron 51' for facilitating discharge of the material delivered outwardly through the openings 47a', etc.

The baffle members, screens and lifting vanes of Figs. 1 and 4 are not shown in Fig. 8, which illustrates the use of a plain cylindrical shell whose interior is free from any such obstructions or projections for controlling the lifting and the longitudinal movement of the material within the drum. It will be understood that a shell of this type may also be used in connection with the material inlet and material outlet means shown in the first described form of the invention, and also that the baffle members, screens and lifting vanes shown in Figs. 1 and 4 may, if desired, be provided in the interior of the drum in connection with the material inlet and material outlet means shown in Figs. 8 to 12 inclusive. It will also be noted in Fig. 8 that the openings 28a', etc. through which the material is delivered into the interior of the drum are somewhat removed longitudinally from the entrance into the tubular outlet passage 10. There will, therefore, be little or no tendency for material delivered through said openings to be picked up by the gas and carried out of said passage and I have, therefore, shown in this case no deflector member corresponding to the deflectors 30 of Figs. 1 and 2, although it will be understood that if desired similar deflector means may also be provided in this case.

The operation of the material inlet and material outlet means of this last form of the invention has been already described in connection with the description of said means, and the operation is otherwise similar to that of the form first described, with the exception that when a smooth walled cylindrical shell free from interior obstructions or projections is employed, as shown, the material will simply pass longitudinally through the rotating shell, while being continually lifted at the rising side of the shell due to friction of the shell wall, so as to be tumbled or caused to roll over and over, and fall through and in contact with the gaseous drying medium. The dried material delivered over the apron 51' may be received in any suitable storage means or on suitable conveying or handling means.

A further modification in the arrangement of the material delivering passage means is

shown in Figs. 13 to 16 inclusive. This arrangement is illustrated only in connection with the passage means for effecting discharge of the dried material from the drum, but it will be understood that it may also be applied in connection with the passage means for effecting feeding of the material to be dried into the drum. The cylindrical rotatably mounted shell is shown at 1 and the end plate thereof at 3''. Said end plate is shown as provided with a portion 81 extending outwardly beyond the shell 1 and constituting an intermediate partition plate, and other partition plates 82 and 83 are also provided, parallel to and spaced at opposite sides from said plate 81. A cylindrical wall 84 connects the outer edges of all of said partition plates. An annular partition plate 85, concentric with the shell 1 and partition plate 84 and equally spaced therebetween, extends across between the plates 81 and 82, while similar partition plates 86, spaced at suitable intervals extend, across between the plates 81 and 83, the innermost of said plates 86 being spaced somewhat outwardly from the cylindrical fire box 31, so as to provide a discharge space 48''. The shell 1 is provided with three openings 44a'', 44b'' and 44c'', establishing communication from the interior of said shell into the space between said shell and the partition plate 85, while said partition plate is provided with three openings 88. Adjacent said last mentioned openings are provided inclined deflector plates 89 adapted to guide material through said openings from the space inside partition plate 85 to the space between said partition plate and the outer wall 84. Plate 81 is provided with three openings 91 establishing communication from said last mentioned space to the space at the opposite side of plate 81 and between the outer wall 84 and the first intermediate plate 86, and inclined deflector plates 92 are provided adjacent said openings for guiding the material therethrough. The two intermediate plates 86 are provided with openings 93, and inclined deflector plates 94 are provided adjacent said openings for guiding the material therethrough. The innermost of plates 86 is provided with three openings 47a'', 47b'' and 47c'' leading into the discharge space 48'', and deflector plates 96 are also provided adjacent said last mentioned openings for directing the material therethrough.

It will be seen that in this case three separate passage means are provided as indicated at 49a'', 49b'' and 49c'', said passages being defined by the shell 1, the plates 81 to 86 inclusive, and the several deflector plates 89, 92, 94, and 96. Said passages extend from the openings 44a'', etc. and are displaced first outwardly, then longitudinally of the drum, and finally inwardly

thereof, to the openings 47a'', etc. In the rotation of the drum, the material will pass through the openings 44a'', etc., around through said passages, and out through the 5 openings 47a'', etc. into the discharge space 48''. The material in the lower portions of said passages will as before form an effective seal to prevent inflow of air or outflow of drying medium therethrough. This form of 10 the invention may also be provided with an outwardly flared discharge lip 51'' for facilitating delivery of material from the space 48'' into any suitable storage or conveying means or the like.

15 I claim:

1. A rotary drying apparatus comprising a rotatably mounted drum, means at one end of said drum defining passage means for delivering material to be dried into the 20 drum, said passage means extending around the axis of the drum throughout at least substantially 360° and opening exteriorly of the drum at one end and opening into the interior of the drum at the other end and 25 being so disposed as to effect movement of material from the exterior opening to the interior opening upon rotation of the drum in its normal direction, means at the other end of the drum defining passage means for 30 delivery of dried material from the interior of the drum to the exterior thereof, said last named passage means also extending around the axis of the drum throughout at least substantially 360° and opening into the 35 interior of the drum at one end and opening exteriorly of the drum at the other end and being so disposed as to effect movement of material from the interior opening to the exterior opening thereof upon rotation of said 40 drum in its normal direction, means for rotating said drum in said normal direction to cause material to be dried to enter through said first named passage means and to pass longitudinally through said drum and to be 45 discharged through said last named passage means, and means for heating the material passing through the drum.

2. A rotary drying apparatus comprising a rotatably mounted drum, means at one end 50 of said drum defining passage means for delivering material to be dried into the drum, said passage means extending around the axis of the drum throughout at least substantially 360° and opening exteriorly of the drum at 55 one end and opening into the interior of the drum at the other end and being so disposed as to effect movement of material from the exterior opening to the interior opening upon rotation of the drum in its normal direction, means at the other end of the drum defining 60 passage means for delivery of dried material from the interior of the drum to the exterior thereof, said last named passage means also extending around the axis of the drum 65 throughout at least substantially 360° and

opening into the interior of the drum at one end and opening exteriorly of the drum at the other end and being so disposed as to effect movement of material from the interior opening to the exterior opening thereof upon 70 rotation of said drum in its normal direction, and means including passage means communicating with the central portions of said drum for effecting passage of gaseous drying medium therethrough.

3. In a rotary drying apparatus, a rotatably mounted drum, means at one end of said drum mounted so as to rotate with said drum and defining passage means extending around the axis of the drum throughout at least substantially 360°, said passage means opening exteriorly of the drum at one end and opening to the interior of the drum at the other end and being so disposed as to effect movement of material from the exterior opening to the interior opening upon rotation of the drum in its normal direction, means defining an annular material receiving space outside the drum and adjacent the exterior opening of said passage means, and so disposed as to cause material to pass therefrom through the exterior opening upon rotation of said drum in said normal direction, and means for rotating said drum in said normal direction.

4. In a rotary drying apparatus, a rotatably mounted drum, means defining a central outlet passage for spent drying medium at one end of said drum, said passage being of materially smaller diameter than said drum, means at said end of the drum defining material inlet passage means extending around said drum throughout at least substantially 360° and outside the cross section of said outlet passage, said material inlet passage means opening at one end exteriorly 100 of the drum and opening at the other end into the interior of the drum, means for delivering material into said exterior opening, and means for rotating said drum in such direction as to cause such material to pass by gravity through said passage means to the interior opening thereof.

5. In a rotary drying apparatus, a rotatably mounted drum, means defining a central outlet passage for spent drying medium 115 at one end of said drum, said passage being of materially smaller diameter than said drum, means at said end of the drum defining material inlet passage means extending around said drum throughout at least substantially 360° and outside the cross section of said outlet passage, said material inlet passage means opening at one end exteriorly of the drum and opening at the other end into the interior of the drum adjacent the periphery thereof, means for delivering material into said exterior opening, means for rotating said drum in such direction as to cause such material to pass by gravity through 120 said passage means and through said interior 125

- opening, and deflector means positioned between said interior opening of said material inlet passage means and said drying medium outlet passage, so as to prevent material falling from said interior opening from entering the outflowing drying medium immediately adjacent said outlet passage.
6. In a rotary drying apparatus, a rotatably mounted drum, means at one end of said drum defining a plurality of separate material inlet passages, each extending around said drum throughout at least substantially 360° , each of said passages having an opening at one end communicating with the exterior of the drum and an opening at the other end communicating with the interior of the drum and being progressively displaced in a direction from said exterior opening toward said interior opening, the exterior and interior openings of the respective passages being substantially equally spaced around the axis of the drum, means for delivering material into position to pass by gravity through said exterior openings when at the lower part of the drum, means for rotating said drum in such direction as to effect movement of such material through said passages from said exterior openings to said interior openings, and means extending through said end of the drum and separately from said material inlet passages and defining an outlet passage for gaseous drying medium from the interior of said drum.
7. In a rotary drying apparatus, a rotatably mounted drum, means at one end of said drum defining an annular material receiving space outside the drum and comprising an annular lip adapted to retain material within said space, the diameter of the inner edge of said lip being materially greater than the diameter of said drum whereby material to be dried may be delivered into said space at a level below the lower portion of the drum at said end, means defining passage means extending around said drum throughout at least substantially 360° , said passage means having an exterior opening at one end communicating with said material receiving space and an interior opening at the other end communicating with the interior of said drum and being progressively displaced inwardly toward the axis of said drum from said exterior opening toward said interior opening, and means for rotating said drum in such direction as to cause material to pass by gravity around within said passage means from said exterior opening to said interior opening.
8. In a rotary drying apparatus, means defining a centrally disposed outlet passage for spent drying medium leading from one end of said drum and of smaller diameter than said drum, means defining an annular material receiving space outside said end of said drum comprising an annular lip adapted to retain material within said space, the diameter of the inner edge of said lip being materially greater than the diameter of said drum, means for effecting movement of material from said material receiving space into the interior of said drum upon rotation of said drum, a stack communicating with said outlet passage, means for collecting solid material settling from the drying medium within said stack at a point below said communicating outlet passage, and means for delivering material so collected to said material receiving space by gravity at a point below said outlet passage.
9. In a rotary drying apparatus, a rotatably mounted drum, means defining an inlet passage for hot gaseous drying medium extending through one end of said drum substantially centrally thereof and of materially smaller diameter than said drum, means at said end of the drum defining material outlet passage means extending around the axis of said drum throughout at least substantially 360° and outside the cross section of said gaseous medium inlet passage, said material outlet passage means having at one end an interior opening communicating with the interior of the drum and positioned to permit passage of material from the drum through said opening by gravity upon rotation of the drum and having at its other end an exterior opening communicating with a space outside the drum and positioned to permit discharge of material from said passage means through said last named opening by gravity upon rotation of said drum, and means for rotating said drum in such direction as to cause material to pass by gravity through said passage means from said interior opening to said exterior opening thereof.
10. In a rotary drying apparatus, a rotatably mounted drum, wall means closing the major portion of one end of said drum, means defining an inlet passage for hot gaseous drying medium extending through said wall means substantially centrally of the drum and of materially smaller diameter than said drum, means at said end of the drum defining material outlet passage means extending around the axis of said drum throughout at least substantially 360° and outside the cross section of said gaseous medium inlet passage, said material outlet passage means having at one end an interior opening communicating with the interior of the drum adjacent the periphery thereof and positioned to permit passage of material from the drum through said opening by gravity upon rotation of the drum and having at its other end an exterior opening positioned to permit discharge of material there-through by gravity upon rotation of said drum, means defining an annular discharge space outside said wall means in position to

receive material discharges through said exterior opening, an annular discharge apron adjacent said discharge space and of materially smaller diameter than said drum, 5 and means for rotating said drum in such direction as to cause material to pass by gravity through said passage means from said interior opening to said exterior opening thereof.

10 11. In a rotary drying apparatus, a rotatably mounted drum, means at one end of said drum defining a plurality of separate material outlet passages, each extending around said drum throughout at least substantially 15 360° , each of said passages having an interior opening at one end communicating with the space inside the drum and an exterior opening at the other end communicating with the space outside the drum and being progressively displaced in a direction from said interior opening toward said exterior opening, the interior and exterior openings of the respective passages being substantially equally spaced around the axis of the drum, and being 20 so disposed as to permit passage of dried material therethrough by gravity into and out of the corresponding passages upon rotation of said drum, means for rotating said drum in such direction as to effect movement of dried 25 material through said passages from said interior openings to said exterior openings, and means extending through said end of the drum and defining an inlet passage for gaseous drying medium to the interior of said drum and separately from said material outlet passages.

12. In a rotary drying apparatus, a rotatably mounted drum, means extending through one end of said drum and secured thereto 40 and defining a combustion chamber communicating with the exterior and with the interior of said drum, burner means extending within said combustion chamber, means at said end of the drum defining an annular 45 discharge space surrounding said combustion chamber and separate therefrom, an annular discharge apron adjacent said discharge space, said discharge space and apron being of materially less diameter than said drum, 50 means defining passage means extending around said drum throughout at least substantially 360° , said passage means having an interior opening at one end communicating with the space inside the drum and an exterior opening at the other end communicating with said discharge space and being progressively displaced inwardly toward the axis of said drum from said interior opening 55 toward said exterior opening, and means for rotating said drum in such direction as to cause material to pass by gravity around within said passage means from said interior opening to said exterior opening.

60 13. In a rotary drying apparatus, a rotatably mounted drum, means for rotating said

drum, means for feeding material to be dried longitudinally through said drum, means for maintaining a flow of gaseous drying medium through said drum, and annular baffle members projecting inwardly from the wall of said drum and spaced longitudinally thereof, 70 said baffle members being inclined inwardly in the direction opposite to the direction of longitudinal movement of the material to be dried.

75 14. In a rotary drying apparatus, a rotatably mounted drum, means for feeding material to be dried longitudinally through said drum, means for maintaining a flow of gaseous drying medium through said drum, means for rotating said drum, and an annular screen member extending inwardly from the peripheral wall of said drum and inclined inwardly in the direction opposite to the direction of longitudinal movement of the material to be dried, 80 said screen member having a relatively large central opening for passage of gaseous drying medium therethrough.

85 15. In a rotary drying apparatus, a rotatably mounted drum, means for feeding material to be dried longitudinally through said drum upon rotation thereof, means for maintaining a flow of gaseous drying medium through said drum, means for rotating said drum and an annular screen member extending inwardly from the peripheral wall of said drum intermediate the ends thereof, and inclined inwardly in the direction opposite to the direction of longitudinal movement of the material to be dried, 90 said screen member having a relatively large central opening for passage of gaseous drying medium and also having an additional opening in its inclined surface of materially greater size than the regular meshes of said screen member.

95 In testimony whereof I have hereunto subscribed my name this 6th day of March 1930.

HARRY L. CORWIN.
